UNITED STATES PATENT OFFICE.

LAMAR H. SHOVER, OF MILWAUKEE, WISCONSIN, ASSIGNOR TO PANAY-HORIZONTAL SHOW-JAR CO., OF MILWAUKEE, WISCONSIN.

CANDY JAR.

Application filed December 12, 1922, Serial No. 606,422. Renewed August 14, 1926.

This invention relates to food jars and is particularly directed to a candy jar for the dispensing of candy.

Objects of this invention are to provide a jar in which a hygroscopic material is positioned within the jar in order to keep the contents dry, in which means are provided for removably retaining such material, in which a simple and effective means are provided for holding the container closed and upon the cover, and in which a well is provided for retaining the collected moisture.

An embodiment of the invention is shown in the accompanying drawings, in which

Figure 1 is an inner face view of the cover of a candy jar, and

Figure 2 is a fragmentary view partly in section of the complete candy jar with the cover in position, such jar occupying its correct angular position.

The jar consists of a glass body portion 1, preferably of substantial thickness to provide the requisite strength. The end of the jar is covered by means of a seating member, or angular ferrule conforming to the contour of the jar and consisting of outer and inner walls 2 and 3, and an intermediate connecting portion 4. This member is secured to the glass jar by pouring cement 5 between the end of the glass jar and the walls of this member, thereby firmly retaining the member in position. This member is preferably provided with outer and inner ribs 6 and 7, projecting outwardly from its outer surface and forming a channel for the reception of a rubber or other gasket 8. Spaced lugs 9 are carried by the ferrule.

The cover or top 10 may be of metal and is provided with spaced lugs 11 which are pivotally associated with the lugs 9 by means of the pintle 12. A spring 13 is coiled about the pintle and bears at one end against the cover and at its other end against the ferrule thereby tending to hold the cover in closed position. In order to secure an air tight joint, it may be desirable to provide a V-shaped inwardly directed rib 14 upon the cover which cooperates with a groove formed in the gasket 8 to effect a perfect sealing when the cover is closed. If desired, notches 15 may be provided in the lugs 11 which may cooperate with a latching device 16 pivoted to the lugs 9 to temporarily hold the cover in open position, as for instance, when the jar is being filled.

Upon the inner side of the cover, a pad of hygroscopic material 16 is provided for absorbing moisture from the interior of the jar and thereby maintaining the interior in a dry state to prevent the candy or other food from becoming moist and sticky. This pad may be formed in any desired manner, as for instance, alternate layers of calcium chloride and blotting paper or, in fact, in any desired manner. The container for the pad comprises a back 17 bearing against the inner side of the cover 10, and provided with flanges 18. A cover 19 provided with flanges 20 completes the casing, the flanges 20 cooperating with the flanges 18 to form a tight and secure joint. The member 19 is provided with a plurality of apertures 21 which are distributed throughout substantially its entire area but which terminate short of the bottom portion of the member 19, thereby leaving an imperforate portion 19'. This imperforate portion forms, in effect, a well for the retention of any moisture that may otherwise drip from the container. At approximately the central portion of the cover 19, a depression 22 is formed and is provided with an aperture thru which a screw 23 passes. The screw passes thru the back 17 of the container, thru the jar cover 10, and thru the foot 24 of a looped, or curved, handle 25, the head of the screw being conveniently positioned upon the outer side of the cover. A knurled nut 26 is screwed upon the inner end of the screw and is positioned within the recessed or depressed portion 22.

When it is desired to renew the hygroscopic pad or cake, the nut 26 may be loosened and the container removed. Thereafter the cover 19 of the container may be removed and a new pad inserted. It is to be noted that this arrangement of fastening means for the cover of the container also retains the container in position upon the cover of the jar, and in addition thereto, holds the handle 25 in position. This fastening means is extremely simple and may be readily manipulated by an unskilled person. The nut, it will be noted, does not project beyond the inner edge of the container, and therefore does not produce an unsightly appearance when the cover is open. If it is desired, a shield, or flap, 27 may be pivotally joined to lugs 28 from upon the inner side of the cover 10. This seal or flap is

adapted to close the gap between the lower portion of the cover and the ferrule when the cover is opened, so as to prevent the falling of candy into such space. It is to be noted that these candy jars are usually employed in stores where candy is dispensed and are arranged in racks with the outer ends of the jars in substantially the same plane. It is found that with this type of jar, a number may be locked in closed position by passing a bar (not shown) between the handle 28 and the cover 10 and locking the bar in position. It is to be noted that the peculiar construction of the handle greatly facilitates this operation.

It will be seen that a candy jar has been provided which is so organized that the candy will be prevented from becoming sticky, which is provided with a simple renewable hygroscopic device, which is provided with a simple form of securing means for holding the hygroscopic device in position upon the door and for holding such device itself closed.

25 I claim:

1. The combination with a receptacle, of a cover therefor, a perforated container removably positioned upon the inner side of said cover, a moisture regulating substance in said container, a handle positioned upon the outer side of said cover, and unitary means for securing the container and handle on to opposite sides of said cover.

2. The combination with a receptacle, of a cover hinged thereto, a container positioned upon the inner side of said cover, and having a perforated top, a moisture regulating pad carried within and housed by said container, a handle positioned upon the outer side of said cover, and unitary means extending through the container and cover

for securing the container in position against the inner side of the cover and for securing the handle in position on to the outer side of said cover.

3. A candy jar comprising a hollow body portion having an open end, a cover hinged to said body portion and adapted to seal said open end, resilient means tending to move said cover to closed position, a two part container having a perforated top and positioned upon the inner side of said cover, said top having a depressed portion, a screw passing thru said cover and said container, and a nut located within said depressed portion and threaded upon said screw, whereby when said nut is tightened, said container is retained in place and said top is held in position upon the inner side of said cover.

4. A candy jar comprising a hollow body portion having an open end, a cover hinged to said body portion and adapted to seal said open end, resilient means tending to move said cover to closed position, a two part container having a perforated top and positioned upon the inner side of said cover, said top having a depressed portion, a screw passing thru said cover and said container, a nut located within said depressed portion and threaded upon said screw, whereby when said nut is tightened, said cover is retained in place and said top is held in position upon the inner side of said cover, and a handle positioned upon the outer side of said cover and secured in place by said screw.

In testimony that I claim the foregoing I have hereunto set my hand at Milwaukee, in the county of Milwaukee and State of Wisconsin.

LAMAR H. SHOVER.
